US00D789459S

(12) **United States Design Patent** (10) Patent No.: **US D789,459 S**
(45) Date of Patent: **** Jun. 13, 2017**

(54) CONSTRUCTION SET ELEMENT		
(71) Applicant: MEGA Brands Inc. , Montreal (CA)	D314,405 S	2/1991 Pedersen et al.
(72) Inventors: Anthony Ramière , Montreal (CA); Jonathan Brault , Rougemont (CA)	D315,376 S	3/1991 Meyer
(73) Assignee: MEGA Brands Inc. , Montreal, Quebec (CA)	D315,381 S	* 3/1991 Meyer D21/505
(**) Term: 15 Years	D317,480 S	6/1991 Skov et al.
(21) Appl. No.: 29/539,001	D317,482 S	6/1991 Michaelsen et al.
(22) Filed: Sep. 10, 2015	D317,635 S	6/1991 Eggert et al.
(51) LOC (10) Cl. 21-01	D318,077 S	7/1991 Larsen et al.
(52) U.S. Cl. USPC D21/505	D318,696 S	7/1991 Hoyer et al.
(58) Field of Classification Search	D319,267 S	8/1991 Hoyer et al.

CLAIM

The ornamental design for a construction set element, as shown and described.

DESCRIPTION

FIG. 1 is a top isometric perspective view of a construction set element showing the new design;

FIG. 2 is a front elevational view of the construction set element of FIG. 1;
FIG. 3 is a rear elevational view of the construction set element of FIG. 1;
FIG. 4 is a right side elevational view of the construction set element of FIG. 1;
FIG. 5 is a left side elevational view of the construction set element of FIG. 1;
FIG. 6 is a top plan view of the construction set element of FIG. 1;
FIG. 7 is a bottom plan view of the construction set element of FIG. 1;
FIG. 8 is a front elevational view of the construction set element of FIG. 1, with its circular component in a second position;
FIG. 9 is a front elevational view of the construction set element of FIG. 1, with its circular component in a third position;
FIG. 10 is a front elevational view of the construction set element of FIG. 1, with its circular component in a fourth position;
FIG. 11 is a top isometric perspective view of another embodiment of a construction set element showing the new design;

FIG. 12 is a front elevational view of the construction set element of FIG. 11;
FIG. 13 is a rear elevational view of the construction set element of FIG. 11;
FIG. 14 is a right side elevational view of the construction set element of FIG. 11;
FIG. 15 is a left side elevational view of the construction set element of FIG. 11;
FIG. 16 is a top plan view of the construction set element of FIG. 11;
FIG. 17 is a bottom plan view of the construction set element of FIG. 11;
FIG. 18 is a front elevational view of the construction set element of FIG. 11, with its circular component in a second position;
FIG. 19 is a front elevational view of the construction set element of FIG. 11, with its circular component in a third position; and,
FIG. 20 is a front elevational view of the construction set element of FIG. 11, with its circular component in a fourth position.
The broken lines and unshaded areas form no part of the claimed design.
